ROBERT M. BARTHELMESS AND CHARLES C. MILLAR, OF SAVANNAH, GEORGIA.

Letters Patent No. 83,591, dated November 3, 1868.

IMPROVED CAR-COUPING.

The Schedule referred to in these Letters Patent and making part of the same.

To all whom it may concern:

Be it known that we, ROBERT M. BARTHELMESS and CHARLES C. MILLAR, of Savannah, in the county of Chatham, and State of Georgia, have invented a new and improved Car-Coupling; and we do hereby declare that the following is a full, clear, and exact description thereof, reference being had to the accompanying drawings, making a part of this specification, in which—

Figure 1 is a front view of the buffer-head, latch, and coupling-link.

Figures 2, 3, 4, and 5 are longitudinal sectional views of the coupling and link, showing the link and latch in different positions.

Similar letters of reference indicate corresponding parts in the several figures.

This invention relates to a new and useful improvement on that class of car-couplings wherein a link and latch are employed for connecting the several cars or coaches of a train together, said latch being so arranged and pivoted as to act as a self-coupling.

The invention relates particularly to the self-coupling slotted latch, which plays through a vertical slot, made longitudinally through the upper part of the buffer-head, and which is so hung as to have a vertical bodily movement, and also a longitudinal vibrating movement, so that while it operates as a self-coupler, it can also be readily raised and depressed by hand, like the ordinary coupling-pin.

The nature of our invention consists in a slotted segmental coupling-pin or latch, applied permanently to a buffer-head, by means of a transverse pivot-pin or rivet, so as to have a free vertical bodily movement, and also a vibrating movement, in combination with a concave forward abutment, which is concentric to the axis of motion of the latch, and so arranged that the latter cannot get in such a position that it will bind, or fail to drop, by its own weight, into its proper place when raised, as will be hereinafter described.

To enable others skilled in the art to understand our invention, we will describe its construction and operation.

The buffer-head is made with a flaring bell-mouth, extending back into a channel having rectangular sides, and terminating in a receptacle, *a*, for receiving the end of the coupling-link *A*, and keeping this link in a horizontal position, as shown in fig. 3.

This buffer-head *B* has a slot, *b*, made vertically and longitudinally through it, above the bell-mouth chamber *C*, which slot is of such length as will allow the latch *D* to vibrate freely backward of the position in which it is represented in figs. 2 and 5.

Beneath this slot *b*, and in the same vertical plane, is a depression, *c*, made in the lower part of the buffer-head, for receiving the lower end of the latch *D*, and affording a forward abutment therefor, when the latch is in the position shown in figs. 2 and 5.

The latch *D* is of the form of a segment, with an

eye, *d*, through its upper end, to which is applied a ring, *e*, for raising the latch to uncouple.

This latch *D* has a slot, *f*, through it, through which passes a pin or rivet, *g*, that extends transversely through ears formed on top of the buffer-head.

The ends of the pin *g* are riveted, so that said latch will be permanently attached to the buffer-head.

The oblong slot, *f*, through the latch *D*, is of such length as will allow the latch to be raised sufficiently high to detach the coupling-link *A* from it, and this slot has the same curve as the front edge of the latch.

The front curved edge of the latch *D* is fitted snugly but not tightly against an abutment, *h*, which latter serves, in conjunction with an abutment at *i*, to support the latch at two points, and on both sides of the coupling-link *A*, as shown in fig. 5.

The curved abutment, *h*, pitches the upper end of the latch forward, and causes it to rise and fall bodily in the arc of a circle, so that this latch cannot, under any circumstances, bind, or assume such a position that it will fail to fall properly in position when released, after being raised to allow of the withdrawal of the link.

While this forward abutment, *h*, will prevent the latch *D* from vibrating when raised, it will not prevent it from vibrating back of the position shown in fig. 2 when depressed.

The abutment at *i*, and the eye-piece *d*, on the latch *D*, will prevent the lower end of the latter from being thrown up too high in making a coupling of two cars.

The abutment *h* also serves as a guide, for directing the latch *D* into its recess when the latch is dropped, and it also serves to relieve the rivet-pin *g* from all strain.

The curved back edge of the latch *D* is rounded, so as to conform to the inner surface of the link *A*, therefore there will be little or no wear upon the latch or link, and as the latch is inclined backward, the link will be brought to the position shown in fig. 5, when a train is in motion, going forward, in which position of the link the latch will receive very little strain.

We do not claim the construction of slotted latch for links of cars, shown in the patent of J. M. Gow, granted February 9, 1864, as such construction would not accomplish the result secured by our combined segmental abutment *h* and segmental latch *D*; but having described our invention,

What we claim as new, and desire to secure by Letters Patent, is—

The application, within a longitudinal slot, *b*, through a buffer-head, *B*, of a slotted segmental latch, *D*, of described construction, guided and kept in place by means of a pin, *g*, and curved abutment *h*, substantially as described, and for the purposes set forth.

R. M. BARTHELMESS.
